US0D1001063S

(12) **United States Design Patent** (10) **Patent No.:** **US D1,001,063 S**
(45) **Date of Patent:** **** Oct. 10, 2023**

(54) **CHARGING DEVICE**

(71) Applicant: **Canoo Technologies Inc.**, Torrance, CA (US)

(72) Inventors: **Iliya Bridan**, Long Beach, CA (US); **Richard Kim**, Los Angeles, CA (US); **Nicholas Gronenthal**, Los Angeles, CA (US)

(73) Assignee: **Canoo Technologies Inc.**, Torrance, CA (US)

(**) Term: **15 Years**

(21) Appl. No.: **29/790,260**

(22) Filed: **Nov. 15, 2021**

(51) LOC (14) Cl. **13-02**

(52) U.S. Cl. **D13/107**

CLAIM

The ornamental design for a charging device, as shown and described.

DESCRIPTION

FIG. 1 is a front perspective view of a charging device showing our new design;

FIG. 2 is a front elevation view of the charging device of FIG. 1;

FIG. 3 is a rear elevation view of the charging device of FIG. 1;

FIG. 4 is a right side view of the charging device of FIG. 1; FIG. 5 is a left side view of the charging device of FIG. 1; FIG. 6 is a top view of the charging device of FIG. 1; FIG. 7 is a bottom view of the charging device of FIG. 1; and,

FIG. 8 is a bottom perspective view of the charging device of FIG. 1.

The broken lines shown in the drawings represent portions of the charging device that form no part of the claimed design.

1 Claim, 6 Drawing Sheets
